INVENTOR
Matthew Faloon
De Witt B. Allen.

UNITED STATES PATENT OFFICE.

MATTHEW FALOON, OF BLOOMINGTON, ILLINOIS.

GATE.

SPECIFICATION forming part of Letters Patent No. 243,695, dated July 5, 1881.

Application filed April 1, 1881. (No model.)

To all whom it may concern:

Be it known that I, MATTHEW FALOON, of Bloomington, in the county of McLean, and in the State of Illinois, have invented certain new and useful Improvements in Gates; and I do hereby declare that the following is a full, clear, and exact description thereof, reference being had to the accompanying drawings, and to the letters of reference marked thereon, making a part of this specification, and in which—

Figure 1 is a perspective view, and Fig. 2 is a detail view, of my invention; Fig. 3, detail view of a modification forming the lower hinge of the gate.

My invention relates to certain new and useful improvements in swinging gates, and more particularly to the class of metallic and barbed-wire gates; and the invention consists in novel features of construction and combination and arrangement of parts, all as will be hereinafter fully described, and specifically pointed out in the claims.

In the drawings, A represents the gate, constructed wholly of metal and in the following manner. The upper and lower longitudinal rails, B C, and the front, central, and rear vertical rails, D E F, are formed of tubular metallic rods, and are connected together by T-shaped elbow and cross tubular metallic couplings d e f, all as clearly shown in Fig. 1.

G and H H represent, respectively, intermediate longitudinal metallic strip and twisted barbed wires, connected to the vertical tubular rails D E F by wire fasteners g, and connected together and to the upper and lower longitudinal tubular rails, B C, by intermediate vertical twisted wires, h h.

I represents a cluster-post, composed of two or more metallic tubes, i, crossing each other near their upper ends, and connected together at their upper ends by a metallic cap, J. Two of said tubes are connected together near their lower ends by a metallic coupling or a bent metallic plate, j.

The upper tubular rail, B, passes through and beyond the coupling f at the upper rear end of the gate, and its extended end, b, is bent at right angles and passed down through the cap J, for forming the upper hinge or journal of the gate.

A T-shaped metallic coupling, K, is mounted

and secured on the rear vertical tubular rail, F, near the lower end thereof, and to which is secured a right-angled tubular rod, k, journaled in or through the tubular coupling or bent metallic plate j, for forming the lower hinge or journal of the gate.

The upper end of the central cross-coupling, connecting the central vertical and upper longitudinal rails, is closed by a plug, f', having formed therewith or secured thereon a metallic guide loop or eye, f², through which passes the front end of a tubular rod, L, which extends backward beyond the rear end of the gate and through a cross tubular coupling, l, having its lower end journaled in a metallic tube, l', connected to the upper end of one of the tubes i of the cluster I or to the cap J.

The rear end of the rod L, which extends some distance beyond the coupling l, is turned up at right angles, and has journaled thereon a metallic spool, M, around which passes the operating-cords m m, and which are prevented from working off said spool by a wire, m', connecting the two flanges of the spool, and between which and the main body of the spool said cords pass.

The cords m m are connected at their inner ends to the rear end of a longitudinal barbed wire, N, which extends forward through a metallic loop or eye, n, (connected to or formed on top of a plug, n', that closes the upper end of the cross-coupling l,) and a short distance beyond the front end of the gate, and is connected to the upper end of a metallic spring-latch, O, that engages with a metallic catch, o, when the gate is closed, secured to a tube or coupling, p, mounted and secured on the tubular metallic gate-post P.

The spring-latch O passes down through a guide-loop, o', projecting from and secured to the coupling d at the front and upper end of the gate, and is connected or secured at its lower end to or near the lower end of the front vertical tubular rail, D.

The cords m m pass through the metallic guide-loops m² m² formed with or otherwise secured to plugs r, that close the upper ends of the metallic tubular posts R R', and are provided with weights r' r', for keeping said cords always taut. The posts R R are arranged on opposite sides and a short distance from and on a line with the rear end of the gate, and

against which it strikes when opened to either side, and the posts R' R' some distance back of the posts R R, but in the path of a circle relative to the spool M on the rear end of the rod L, all as clearly shown in Fig. 1, whereby the cords are adapted to be more easily worked and with less friction.

The lower ends of the tubular gate-post P, tubular posts R R R' R', and the tubular rods 10 i, forming the cluster-post I, are first dipped in tar or thick lead-paint and inserted in the upper ends of tubular tiles S, which are then dipped in boiling tar above the tops of the tiles. The tiles, after having been treated as above 15 described, are forced into holes bored in the ground for their reception. This construction of posts forms the subject of another application for Letters Patent, bearing even date with this case, for improvement in metallic fences, 20 and it is therefore deemed unnecessary to point out the advantages resulting from such construction, as it is designed to be used both in connection with the fence and gate, but is not broadly claimed in this case.

25 In connecting the various portions of the gate and its appendages by the different forms of couplings and the plugs for closing the upper ends of the posts and couplings, they may or should be dipped in tar or thick lead-paint, 30 in order to form water-tight joints.

The operation of my improved gate is as follows: The gate being closed, in order to open it from either side by persons in vehicles, the operator pulls on either of the cords m, 35 which pulls the wire N backward and releases the spring-latch O from the catch o, and further pulling on the same cord turns the gate around against the post R, through the medium of the pivoted rod L, connected to the gate.

40 After passing through the gate the operator, by pulling on the other cord m, repeats the operation just described, but in the opposite direction, and the gate is closed.

Having thus fully described my invention, 45 what I claim as new, and desire to secure by Letters Patent, is—

1. In a metallic gate, the combination, with the tubular rails B D and guide-loop o', of the T-shaped coupling d, for connecting said parts

together, substantially in the manner herein 50 shown and described.

2. In a metallic gate, the combination, with the pivoted rod L and tubular rails B E, of the cross-coupling f, provided with the plug f', having guide loop or eye f², for connecting 55 said parts together, substantially in the manner herein shown and described.

3. The combination, with a swinging gate, of the cluster-post I, to which said gate is hinged or pivoted, composed of the metallic 60 tubes i, crossing each other near their upper ends and connected together by cap J and metallic coupling or plate j, substantially as and for the purpose herein shown and described.

4. The combination, with the gate A, of the 65 rod L, connected thereto and having the pivoted cross-coupling l mounted thereon, the part I, upon which the coupling is pivoted, and the plug n', for closing the upper end of said coupling, provided with a guide loop or eye, 70 n, for the reception of the wire N, substantially in the manner as and for the purpose herein shown and described.

5. The combination, with the gate A and spring-latch O, of the pivoted rod L, connected 75 to said gate, and provided with the spool M at the rear end thereof, the sliding or longitudinally movable wire N, connected to said spring-latch, and the operating-cords m m, connected to the rear end of said wire N and 80 passing around said spool M, the several parts constructed and arranged relatively to each other substantially in the manner herein shown and described.

6. The cluster gate-post I, composed of the 85 tubes i, crossing each other near their upper ends and connected by cap J at their top ends, and provided at their lower ends with the tubular ground tiles S, substantially as herein shown and described.

In testimony that I claim the foregoing I have hereunto set my hand this 23d day of February, 1881.

MATTHEW FALOON.
